PANTS GUARD AND REFLECTOR

Zeno A. Bruegger, Boise, Idaho

Application November 27, 1943, Serial No. 512,020

2 Claims. (Cl. 88—80)

The invention relates to a reflector attachment for trousers, and more especially to a combined trouser guard and reflector.

The primary object of the invention is the provision of an article of this character, wherein the leg portions of trousers can be conveniently held tucked about the limbs of a person, especially one when operating a bicycle or the like, to avoid the catching of these portions in working parts thereof, and such device serves as a reflector effective for signalling purposes.

Another object of the invention is the provision of an article of this character, which is simple in construction, thoroughly reliable and efficient in its purpose, strong, durable, readily and easily applied and removed, neat in appearance, comfortable, and inexpensive to manufacture.

With these and other objects in view the invention consists in the features of construction, combination and arrangement of parts as will be hereinafter more fully described, illustrated in the accompanying drawing, which discloses the preferred form of the invention, and pointed out in the claims hereunto appended.

In the accompanying drawing:

Figure 1 is a perspective view of the article constructed in accordance with the invention and in applied position.

Figure 2 is a fragmentary sectional view taken on the line 2—2 of Figure 1.

Figure 3 is a view similar to Figure 2 showing a modification.

Figure 4 is a similar view to Figure 3 showing another modification.

Figure 5 is a view similar to Figure 4 showing a further modification.

Figure 6 is a sectional view of a further modification.

Similar reference characters indicate corresponding parts throughout the several views in the drawing.

Referring to the drawing in detail the article constituting the present invention comprises an inherently resilient open loop-like member 5, preferably made from metal and is designed as a pant's clip or guard for engagement about the leg portion 6 of trousers to hold such leg portion tucked about the limb of a person wearing the clip or guard to avoid the leg portion from becoming caught in the working parts of a bicycle or the like when a wearer is riding the same.

A reflector button 7 is mounted on the outer side of the pants guard 5 at any point or slightly to the rear of the vertical center of the guard.

As shown in Figure 2, the reflector button 7 may be secured to the pants guard 5 by a rivet 8 which is carried by the back plate 9 of the reflector button and which passes through an opening 10 in the pants guard 5. The pants guard 5 is provided at its inner side about the opening 10 with a conical recess 11 into which the inner end of the rivet 8 is upset, and the pants guard is provided at its outer side about the opening with a projection 12 which contacts with the rear side of the reflector button 7, whereby to prevent any inward projection of the rivet 8.

In Figures 3, 4 and 5 are shown modified forms of the means for securing the reflector button 7 to the pants guard 5. The form of the reflector button securing means shown in Figure 3 comprises a loop 13 which is secured to the rivet 8 of the reflector button and which embraces the pants guard 5. The loop 13 may be formed of a single strip of metal which is secured centrally between its ends to the rivet 8 and which has its end portions bent into embracing relation to the pants guard 5 to effect the formation of the loop and at the same time secure the reflector button 7 to the pants guard.

In Figure 4 the reflector button attaching means comprises a spring clip 14 which is secured to the rivet 8 of the reflector button 7 and which is adapted to embrace the pants guard 5 with its lower ends located below the lower edge of the pants guard. In Figure 5, the attaching means for the reflector button 7 is in the form of a loop of inverted U-form. The loop 15 is secured to the rivet 8 of the reflector button 7 and is secured to the pants guard by a bolt 16 which passes through the lower ends of the loop in contact with the lower edge of the pants guard. As shown in Figure 6, the clip, which is here designated 14a, for securing the reflector button to the pants guard, may have its outer side recessed for the reception of the reflector button 7a, and has said side thereof provided with tongues 17 which contact with the outer side of the reflector button to secure the button to the clip. If desired, the back plate of the reflector button 7 may be welded directly to the pants guard 5 or to any of the clips 13, 14 or 15.

From the foregoing description, taken in connection with the accompanying drawing, it will be understood that the reflector button 7 may be applied to the pants guard 5 when the latter is placed upon the market or it may be easily and quickly applied to those pants guards already in

use. The location of the reflector button 7 on the pants guard 5 places it at the outer side of the ankle when the guard is applied. It will move in a circular path when the bicycle is being pedalled and will therefore function as a moving signal. The reflector button 7 is secured by its rivet 8 to the loop 13, spring 14 and loop 15, in the manner in which it is secured directly to the pants guard 5, whereby to effect a substantial connection between the reflector button and the pants guard.

What is claimed is:

1. An article of the kind described, comprising a supporting member, a reflector button, an attaching member carried by the reflector button and adjustably mounted on the supporting member, the attaching member formed with a boss engaging the back of the button to space the

same from the supporting member and means on said attaching member for retaining said member on said supporting member.

5 2. An article of the kind described, comprising a pants guard an attaching member formed with a conical boss having a center opening, and a conical recess back of the center opening and communicating therewith adjustably mounted on said pants guard, a reflector button, a rivet carried by the reflector button and passing through the opening in the boss with the recess receiving the head of the rivet, and the boss engaging the rear side of the reflector button to space the same from the attaching member and means on said attaching member for retaining said member on said supporting member.
